United States Patent Office.

ALVAH WORSTER, OF SYRACUSE, NEW YORK.

Letters Patent No. 91,808, dated June 22, 1869.

IMPROVED TRACE-BUCKLE.

The Schedule referred to in these Letters Patent and making part of the same.

To all whom it may concern:

Be it known that I, ALVAH WORSTER, of Syracuse, in the county of Onondaga, and State of New York, have invented a new and useful Improvement in Trace-Buckles; and I do hereby declare that the following is a full, clear, and exact description thereof, which will enable those skilled in the art to make and use the same, reference being had to the accompanying drawings, forming part of this specification, in which—

Figure 1 is a front view;

Figure 2 is an edge view; and

Figure 3 is a sectional edge view.

Similar letters of reference indicate like parts.

This invention consists in a buckle having a flat central body or bar, which is embraced by a hames-tug loop or swinging link, arranged to slide on said central bar in opening or closing the buckle, in such manner that a very snug and easily-operated buckle is obtained, as hereinafter more fully explained.

In the accompanying drawings—

A is the hames-tug, and

B is the tug.

The buckle is formed with a central bar, C, which is embraced by a swinging link, D, secured in the hames-tug by a rivet or screw-bolt, d.

On the front end of the buckle is a fixed tongue, e, fig. 3, which engages with the tug in the usual manner.

The body of the buckle is formed with an elevation or shoulder, c, which bears against the link when strain is brought upon the tug, and this causes the tug and hames-tug to be clamped together with a force proportional to the strain put upon the tug, so that the tongue e is greatly assisted in holding the tug, without liability of injury.

To release the tug, the buckle is backed up by sliding the bar C through the link D, and the tongue e is then withdrawn readily.

The bar C is made with a uniform thickness endwise, but it may be made somewhat of a wedging form, the base of the wedge being at the shoulder c.

By these means I obtain a buckle which is easily operated, and is snug and reliable.

Having thus described my invention,

What I claim as new, and desire to secure by Letters Patent, is—

A buckle having a central bar or body, C c, in connection with the swinging loop D, as and for the purpose herein set forth.

The above specification of my invention signed by me, this 12th day of December, 1868.

ALVAH WORSTER.
